UNITED STATES PATENT OFFICE

NORMAN H. SAUNDERS, OF HOMEWOOD, ILLINOIS, ASSIGNOR TO RESERVE HOLDING COMPANY, OF CHICAGO, ILLINOIS, A CORPORATION OF DELAWARE

AUTOMATIC TELEPHONE SYSTEM

Application filed May 8, 1929. Serial No. 361,311.

The present invention relates to automatic telephone systems in general, but is concerned more particularly with the development of a small unattended exchange designed to serve a small town and the surrounding community; and the broad, general object is the production of new and improved circuit arrangements whereby the apparatus is simplified and improved.

10 A further object is the provision of suitable circuit arrangements for notifying an attendant at a nearby attended exchange when an abnormal condition arises within the unattended exchange of sufficient gravity to warrant the dispatching of a repair man 15 to the unattended exchange to make an adjustment or to perform a repairing operation. It is a further object to provide suitable arrangements for giving the attendant at the attended exchange a distinctly different signal in case an abnormal condition exists of lesser importance in the unattended exchange. It is a feature of the arrangement 20 that both indications may be given over a trunk line between the attended and unattended exchanges while a conversation is proceeding over the trunk line without interfering with the conversation.

25 A further object is to provide an arrangement such that a connector accessible to the lineswitch of a calling line is not used in case it is out of order. This object is realized automatically by the use of plunger lineswitches of the so-called self-aligning type. 30 When the individual fuse of a connector is blown the line relay fails to respond and the lineswitch releases because the trunk tests open. Since the plunger is self-aligning a new trunk is taken. In case the defect in the 35 connector consists in its sticking in an off-normal position, special arrangements are provided for causing the trunk leading to the connector to test open so as to cause the lineswitch to release and automatically realign 40 on a new trunk.

45 A further object is to provide a simplified arrangement for ringing back on party lines when a reverting call is made.

50 A further object is to provide a simple combination one-digit and two-digit connector

which is operated in accordance with two digits when a subscriber's line is being called and is operated in accordance with only one digit in making certain other calls to be hereinafter explained.

55 It is a further object to make provisions for preventing the tying up of all calls to a trunk group by an open or other defective condition of the first trunk of the group.

60 In addition to the foregoing, there are other objects and features of the invention which will be understood best upon a further perusal of the specification in connection with the accompanying drawings comprising Figs. 1 to 13.

65 General description

Referring now to the drawings, they show by means of the usual circuit diagrams a sufficient amount of apparatus in a telephone system embodying the features of the invention 70 to enable the invention to be understood.

75 Figs. 1 to 4 show certain switching apparatus in an attended manual exchange and in an unattended community automatic exchange (abbreviated C. A. X.). The two exchanges are interconnected by the trunk line TL1 extending between Figs. 1 and 2; Figs. 5 to 8 show certain apparatus known as power and supervisory apparatus auxiliary to the switching apparatus in the C. A. X.; and 80 Figs. 9 and 10 show a desirable modification of the apparatus of Figs. 3 and 4, respectively; Fig. 11 shows the code sent out by the code interrupter apparatus of Fig. 7; Fig. 12 shows the sheets on which Figs. 1 to 8 85 are drawn should be placed; and Fig. 13 is a layout of Figs. 9 and 10.

Detailed description

90 A general description of the apparatus having been given, a detailed description of its operation will now be proceeded with. For this purpose it will be assumed that the subscriber at substation A1 desires to converse with the subscriber at substation A2.

95 Local call in the C. A. X.

When the receiver is removed at substation A1, line relay 304 of lineswitch LS1 operates over conductors 301 and 303 and places 100

ground on the private normal conductor 302 at its upper armature, at the same time closing a circuit for the pull-down winding of the magnet 305 at its lower armature. By 5 the ground potential on conductor 302, the line of substation A1 is made busy immediately to the connectors, and, by the closure of the circuit through the lower winding of magnet 305, the plunger arm 306 is operated 10 to force the bank contact springs into engagement. This extends the conductors 301—303 into engagement with conductors 308—310, respectively. As a further result of the operation of the plunger arm 306, the 15 local contact springs thereof connect the upper winding (the bridge-cut-off winding) of magnet 305 to the grounded conductor 302 to form a holding circuit for the lineswitch.

Upon the operation of the bridge-cut-off arm 307, which occurs responsive to the energization of magnet 305 by either winding, line relay 304 and ground are disconnected from conductors 301 and 303, respectively. Relay 304, being slow acting, does not fall 25 back immediately.

Responsive to the extension of the grounded conductor 302 to conductor 309, start relay 311 of the master switch MS1 operates through test wiper 312 and over a branch 30 of conductor 309 and preselects an idle trunk in the usual manner.

In the local connector LC1, line relay 323, whose lower winding is connected to conductor 310 by way of contacts of relays 322 and 321 and whose upper winding is connected to conductor 308 by way of off-normal contacts 332 and contacts of relays 322 and 321, operates over the calling line and closes a circuit for release relay 324 in series with 40 the vertical magnet 335. The vertical magnet does not operate at this time owing to the relatively high resistance of release relay 324. Release relay 324 operates and places ground on the release trunk conductor 45 309 at its upper armature, closing a holding circuit for the lineswitch LS1 through the upper winding of magnet 305 by way of the local contact springs of plunger arm 306. This circuit is closed before the slow-acting 50 relay 304 has had time to fall back.

As a further result of the operation of relay 324, off-normal contacts 332 are shunted at the inner-upper contacts of the relay and ground is placed on locking conductor 344 55 at the middle-upper contacts. This prepares a locking circuit for relays 326, 330, and 331 and closes a circuit through off-normal contacts 334 for the upper winding of relay 326. Relay 326 operates and prepares an operating circuit for vertical magnet 335 at its inner-lower armature.

At the lower armature of relay 324, a point in the circuit of release magnet 336 is opened and ground potential is extended to the tone- 60 start conductor 621 which extends to Fig. 6,

operating the tone-start relay 809 by way of conductor 623, with results to be pointed out hereinafter. This ground potential is supplied through the low-resistance shelf relay 376, common to a shelf of connectors. Relay 376 does not operate because of the relatively 70 high resistance of the tone-start relay 809.

The connection having been extended from the line of substation A1 to the connector LC1, and relay 326 having been operated, 75 dial-tone current now passes from conductor 811 to the lower talking conductor through contacts of relays 330 and 326 and from thence to the calling substation, informing the calling subscriber that he may now dial 80 the desired number.

When the calling device (not shown) at substation A1 is manipulated in accordance with the first digit 8 in the desired number, the line circuit is interrupted a corresponding number of times and line relay 323 of the connector LC1 falls back momentarily each time the line circuit is interrupted. Each time it falls back, line relay 323 opens the initial circuit of relay 324 and short circuits 90 relay 324 by grounding its lower terminal. Each time relay 324 is short circuited, a direct circuit is closed for the vertical magnet 335 by way of the inner-lower contacts of relays 321, 324, 327 and 325, and the inner 95 lower armature, operated, of relay 326. Each time the short circuit is removed from relay 324 upon the reoperation of relay 323, the vertical magnet 335 restores.

By the operation of vertical magnet 335, 100 the wipers 339—343 are raised step by step to the desired level of bank contacts. Although short circuited momentarily each time the line relay falls back, relay 324 remains operated due to the circulating current through its winding. Relay 329 operates in multiple with the vertical magnet 335 each time relay 324 is short circuited and it remains operated throughout the series of impulses in series with relay 324, but it is 105 unable to remain operated indefinitely in series with relay 324 owing to the relatively high resistance of the latter and owing to the shunting effect of magnet 335. Therefore, relay 329 falls back shortly after the 110 termination of the vertical movement. While operated, relay 329 maintains a locking circuit for relay 326 at its inner-upper armature through the upper armature of relay 326 so as to maintain the vertical-magnet circuit intact. When relay 329 falls back, it 115 opens the locking circuit of relay 326 and the latter relay falls back and transfers the operating circuit from the vertical magnet 335 to the rotary magnet 338 by way of the inner-lower armature, normal, of relay 330.

When the next digit is dialled, the rotary magnet 338 operates owing to the fact that the operating circuit is transferred from the vertical magnet to it as explained above. 130

As a result of the operation of the rotary magnet 338, the wipers 339—342 are rotated into engagement with the set of bank contacts in the eighth level in which the line of substation A2 terminates. This bank contact set is shown in the drawings as the first contact set in the eighth level. According to the second digit dialled is the digit 1. The vertical wiper 343 is rotated out of engagement with its contact bank, with which it makes sliding engagement during the vertical movement.

Relay 329 is again operated during the rotary movement, this time in parallel with the rotary magnet. At its upper armature it closes a circuit for the auxiliary relay 328. Upon operating relay 328 disconnects test wiper 340 from the test windings of relays 321 and 330 and connects it instead to the winding of busy relay 327, while relay 329, at its middle lower armature, places a shunt around the inner lower contacts of busy relay 327 so as to prevent the circuit of relay 329 from being interrupted prematurely by the operation of busy relay 327 during the rotary movement in case test wiper 340 passes over grounded test contacts.

The operation following the termination of the rotary movement depends upon whether the called line is busy or idle. Assuming first that the called line is busy, busy relay 327 is operated when the wipers come to rest on the bank contacts of the called line, and, when the calling subscriber finishes dialing and listens, he hears the busy tone caused by an application of busy-tone current from the busy tone conductor 810 through contacts of relay 330 and 327 to the lower talking conductor.

With relay 327 operated and relay 329 at normal, the circuit of relay 329 is opened so that relay 329 cannot operate again. Relay 328 falls back responsive to the de-energization of relay 329 and completes a locking circuit for the busy relay 327 to the locking conductor 344 by way of the middle upper armature of relay 327.

Upon hearing the busy tone, the calling subscriber is expected to replace his receiver and bring about the release of the lineswitch and the connector.

Assuming now that the line of substation A2 is idle when called, the busy relay 327 is not energized when the wipers come to rest on the contacts of the called line and the deenergization of relays 329 and 328 is followed by the energization of relay 330. The circuit of relay 330 is from ground by way of the grounded conductor 344, through the middle-upper armature, normal, of relay 327, ninth-level shaft spring 333 and its left-hand contact, lower winding of relay 330, upper armature of relay 328, middle-upper armature of relay 330, test wiper 340, and thence by way of the bank contact on which

wiper 340 is standing, to battery through the cut-off winding of the lineswitch (not shown) associated with the line of substation A2. The bridge-cut-off relay of the lineswitch associated with the called line now operates and clears the talking conductors of the called line of attachment.

In the connector, when relay 330 energizes by means of its lower winding in the above traced circuit, it locks itself to conductor 344 at its inner-upper armature, at the same time preparing a locking circuit for relay 326 independent of the upper armature of relay 329. At its middle-upper armature, relay 330 disconnects wiper 340 from the test circuit and connects it directly to ground; it prepares a circuit for pick-up relay 331 at its upper armature; it shifts the operating circuit from the rotary magnet 338 to the operating magnet 354 of the associated code selector CS2; it prepares to place ground on the common interrupter start conductor 622 at armature 356; at armature 357 it opens a point in the busy-tone circuit so as to prevent the busy tone from being applied to the line upon the operation of busy relay 327, when it occurs after the code switch is operated; and at its lower armature it opens a point in the dial-tone circuit so as to prevent the dial tone from being heard after the ring-cut-off relay 326 is subsequently operated.

When the next and last digit, the stations digit, is dialled, the resulting impulses are delivered now to the operating magnet 354 of the code switch CS2, owing to the operated condition of the inner-lower armature of relay 330, with the result that the wipers 351 and 352 of the code switch CS2 are advanced to a position corresponding to the code of the called substation. It may be pointed out here that the code switch is arranged to signal any one of ten parties on a called line, it being assumed that half the ringers are connected between one conductor of the line and ground and the other half connected between the opposite conductor of the line and ground. In this way, ten parties may be signalled by means of five codes, the selected code being applied to one conductor or the other depending upon the station called. In the present case, it may be assumed that the stations digit 5 is dialled. The result is that the #5 code is placed on the upper talking conductor of the called line due to the position of wiper 351, and that the lower conductor of the called line is extended by the wiper 352 on its fifth contact to the lower winding of ring-cut-off relay 326. The completion of the two connections just described is of course dependent on the subsequent operation of pick-up relay 331.

When the wipers of the code switch CS2 come to rest and relay 329 falls back, relay 327 is operated through contacts of relay 329

and through the off-normal contacts 353 of the code switch CS2. Upon operating, relay 327 places ground on the common interrupter-start conductor 622 at armature 346 through contacts of relays 330 and 322; at its inner-lower armature it opens the operating circuit; and at its upper armature it connects the pick-up conductor 713 to pick-up relay 331 by way of the upper contacts of relay 330. The ringing interrupter of Fig. 7 and the tone equipment of Fig. 8 are now operating in a manner to be hereinafter described, and during the operation of the ringing interrupter the pick-up conductor 713 is grounded prior to the application of the codes of ringing current, resulting in the operation of relay 331 through contacts of relays 327 and 330. Relay 331 closes a locking circuit for itself and opens its initial circuit at its inner-upper contacts, while at its upper and lower armatures it completes the ringing circuit from the called line to the wipers 351 and 352 of the code switch CS2. The code placed on code conductor #5 reaches the called line by way of wiper 351, signaling the subscriber at substation A2.

When the subscriber at substation A2 responds, a loop is closed across the conductors of his line, whereupon the lower winding of relay 326 is energized over the called line, the current flowing to the called line by way of the fifth contact in its bank, and wiper 352, contacts of relays 326 and 331, and wiper 342. The return circuit to ground is similar except that it follows the upper conductor of the called line and wipers 339 and 351 and is completed by way of #5 code conductor. Upon operating, ring-cut-off relay 326 completes its locking circuit at its inner-upper armature from the grounded conductor 344 by way of the inner-upper armature of relay 330.

At its upper and middle-lower armatures, relay 326 opens the ringing circuit and completes the talking circuit. Back-bridge relay 322 now operates over the called line and reverses the incoming line conductors as regards their connections with the windings of line relay 323, for the purpose of metering or the like. At its lower armature, relay 322 disconnects ground potential from the common interrupter start conductor 622, while at its upper armature it makes a second application of ground potential to the release trunk conductor 309 so as to prevent the release of the line switch LS1 while the connections to the line relay are reversed.

The conversation may now take place.

When the conversation is terminated, the two subscribers replace their receivers. On the assumption that the subscriber at substation A2 replaces his receiver first, back-bridge relay 322 falls back and again reverses the connections of the line relay to their normal condition, at the same time removing the

multiple ground connection from conductor 309 and again applying a ground potential to the interrupter start conductor 622.

When the receiver is replaced at the calling substation, line relay 323 falls back and short-circuits release relay 324, with the result that relay 324 falls back after a slight interval. Upon so doing, it permits the line-switch LS1 to release by removing ground potential from conductor 309 at its upper armature, and it removes ground at one point from conductor 344, but this conductor is now maintained grounded through the off-normal contacts 353 of the code switch CS2, and contacts of relays 329, 328, and 327.

At its lower armature, relay 324 removes ground from the tone-start conductor 621 and closes a circuit for the release magnet 355 of the code switch CS2. The circuit of this magnet includes contacts of relays 321, and 324, and armature 345, operated, as well as the associated release signal relay 376, common to a shelf of connectors. When the release magnet of the code switch CS2 operates, the wipers 351 and 352 are restored to normal, and the off-normal contacts 353 open, allowing relays 327, 330, and 331 to release. When relay 327 releases it disconnects the release conductor from release magnet 355 and connects it to release magnet 336 by way of the off-normal contacts associated therewith. Upon the operation of magnet 336 the wipers 339-342 and 343 are restored to their normal position in the usual manner, and the various off-normal contacts of the connector restore to their normal condition. Upon the falling back of relays 327 and 330 the interrupter-start conductor 622 is again ungrounded.

The connection is now released and the apparatus involved therein is in readiness to be used in establishing subsequent connections.

Reverting call on the line of substation A1

It will be now assumed that the subscriber at substation A1 desires to call another subscriber whose substation is on the same line. In order to do this, the subscriber at substation A1 removes his receiver and obtains dial tone from a local connector in the usual manner, following which he dials the digit 9, followed by the stations digit of the calling station and then the stations digit of the called station. When the digit 9 is dialled, the local connector in use is operated to the ninth level and seizes a ring-back switch, such as the ring-back switch RB1, Fig. 4, in a manner to be described more in detail hereinafter, and the ring-back switch responds to the two stations digits and conditions itself to perform the signalling operation after the calling subscriber hangs up.

It will be assumed that the local connector LC1 of Fig. 3 is the one seized by the line-switch LS1 when the receiver is removed at substation A1, in which case the connector is

prepared for operation in the manner hereinbefore described by the operation of relays 323, 324, and 326.

When the first digit is dialled, the wipers 339—342 are raised opposite the ninth level of bank contacts. The arrangement involving the vertical wiper test 343 is for the purpose of causing the local connector LC1 to act as a single digit connector when a reverting call is made. Since the wipers are now raised to the ninth level, wiper 343 encounters the ninth associated bank contact, which is grounded as may be seen in the drawings. This places a ground potential on the rotary test wiper 341 and also places a ground potential on the regular busy test wiper 340 on account of the fact that the wiper 343 contacts also with the bank contact immediately below the contact on which it is standing, the eighth bank contact in this case. It will be recalled that relays 326, 328, and 329 are in operated condition at the end of every vertical movement. In this case, since wiper 340 is grounded by way of the vertical wiper 343 from ground on its ninth contact and by way of its eighth contact, busy relay 327 is operated and at its inner-upper armature it connects the resistance 337 in parallel with relay 328 so as to form a path for circulating current to make relay 328 slow acting. Relay 328 is ordinarily not slow acting so as not to delay the switching operation when an idle line is reached.

When relay 329 falls back at the end of the vertical movement and opens the circuit of relay 328, relay 328 is slow acting and does not fall back immediately owing to the fact that the resistance 337 is in shunt of it at this time. With relay 328 thus operated, and with relay 329 restored and ground potential encountered by the vertical wiper 343, a circuit from ground is closed for relay 325 by way of wiper 343, the interrupter contacts of rotary magnet 338, and contacts of relays 329 and 328. Upon operating when this circuit is closed, relay 325 closes a locking circuit for itself at its lower armature through the interrupter contacts of the rotary magnet; closes a circuit at its upper armature to hold relay 328 operated; and at its inner-lower armature it disconnects the rotary magnet 338 from in parallel with relay 329 and closes a circuit for the rotary magnet to ground. The rotary magnet operates and it rotates the wipers 339—342 and 343 one step. Near the end of its stroke, magnet 338 opens the circuit of relay 325, whereupon relay 325 falls back and opens the circuit of magnet 338 at its inner lower armature. Obviously, relay 325 opens a point in its locking circuit at its lower armature and opens the circuit of the now slow-acting relay 328 at its upper armature.

The vertical wiper 343 has been rotated away from engagement with its vertical set

of contacts with the result that the further operation depends upon whether the trunk line leading to the first ring-back switch is busy or idle. If it is busy, wiper 341 encounters a grounded contact with the result that relay 325 operates again thereover and busy relay 327 remains operated over the encountered grounded contact and maintains relay 328 shunted by resistance 337 so as to maintain it slow acting. In this case the rotary magnet 338 is operated again and the wipers advance another step. This alternate operation of relay 325 and magnet 338 continues until an idle trunk line is reached, whereupon relay 325 fails to operate again and relay 327 falls back. When relay 327 falls back, the shunt 337 is removed from around the winding of relay 328 and this relay immediately falls back and connects up the test wiper 340.

With relays 327 and 328 both deenergized, a test circuit is closed from ground on conductor 344 to battery on the release trunk conductor 365 by way of wiper 340 and the bank contact on which it is standing. This is under the assumption that the ring-back switch RB1 is idle when tested and is, therefore, seized. The test circuit at this time includes the test winding of switch-through relay 321 instead of the test winding of switching relay 330 on account of the fact that the ninth-level shaft spring 333 is now shifted to its alternate position. The complete circuit for the upper winding of relay 321 is as follows: from ground by way of the grounded conductor 344 (grounded as hereinbefore pointed out at the middle upper armature of relay 324), middle-upper armature, normal, of relay 327, spring 333 and its right-hand contact, upper winding of relay 321, resting contact and upper armature of relay 328, middle-upper armature of relay 330, test wiper 340, the bank contact on which it is standing, conductor 365, lower armature, normal, of relay 402, Fig. 4, jumper 429, upper armature, normal, of relay 425, and resistance 430 to battery.

Upon operating, relay 321 closes a locking circuit for its lower winding at its inner-upper armature to the grounded release conductor 309, and at the same time it joins release conductor 309 to the test wiper 340 by way of contacts of relays 328 and 330. At its inner-lower armature, relay 321 opens a point in the operating circuit; it opens a further point in the release circuit at its middle-lower armature and closes an alternative tone-start circuit; and at its upper and lower armatures it disconnects the incoming conductors 308 and 310 from the talking circuit (including the front and back-bridge relays 323 and 322) and extends them directly to the wipers 339 and 342. When this is done, line relay 424 of the ring-back switch RB1, Fig. 4, which is connected to con-

ductors 364 and 366 through contacts of relay 421, operates over the calling line and through the wipers 339 and 342 of the local connector LC1 and closes a circuit for release 5 relay 425 through the operating magnet 433. Release relay 425 energizes and prepares the switch for operation at its lower armatures and closes a holding circuit for the connector and line-switch at its upper armature by 10 placing a holding ground potential on conductor 365. Since conductor 365 is now joined, as above pointed out, to release trunk conductor 309 of the local connector LC1, the line switch LS1 remains operated and 15 relay 321 of the connector LC1 remains energized through its lower winding.

When line relay 323 is cut off by the operation of the upper and lower armatures of relay 321, it falls back and short circuits 20 relay 323, with the result that relay 324 falls back after an interval, but the connector LC1 does not release owing to the fact that relay 321 is operated.

The calling subscriber now dials the digit 25 corresponding to his own station suffix, whereupon the line relay 424 of the ring-back switch RB1 falls back a corresponding number of times. Each time it does so, it closes at its make-before-break contacts a circuit 30 for the operating magnet 433 of the digit register DR1 as follows: from ground by way of the resting contact and middle-lower armature of relay 428, contacts controlled by line relay 424, inner-lower armature of release relay 425, inner-lower armature, normal, of relay 428, and the inner-lower armature, normal, of relay 427 to battery by way 35 of the operating magnet 433. By the operation of operating magnet 433, wipers 435 and 436 are positioned on the contact set 40 corresponding to the suffix assigned to the calling substation. It will be noted that relay 425 is short circuited on each impulse delivered to the operating magnet but this 45 relay remains operated in the manner pointed out in connection with release relay 324 of the local connector LC1. Relay 426 operates in multiple with the operating magnet upon the first closure of the circuit to the 50 latter and it remains operated throughout the series of deenergizations of relay 424 for the reason pointed out in connection with relay 329, Fig. 3.

When relay 426 falls back at the end of the 55 stations digit assigned to the calling station, the lower winding of transfer relay 427 is energized through the off-normal contacts 432 of the digit register DR1 and through the normally closed contacts controlled by the 60 armature of relay 426.

The calling subscriber now dials the digit assigned to the desired station on the calling line, whereupon line relay 424 is again deenergized a corresponding number of times. 65 Each deenergization occurring at this time

results in the closure of a circuit for the operating magnet 438 of the digit register DR2 owing to the operated condition of the relay 427, which transfers the operating circuit from magnet 433 to magnet 438 at its inner lower armature. It will be noted that, when relay 426 operates at the beginning of the second series of impulses, the initial circuit of relay 427 is opened, but an alternate circuit is closed for the relay through its upper winding by way of its upper contacts. 70

When relay 426 falls back at the end of the digit, it completes a circuit for the lower winding of relay 428 through off-normal contacts 437, and again completes the initial circuit for the lower winding of relay 427. Relay 428 disconnects the operating circuit from magnet 438 at its middle-lower armature and transfers it instead to relay 421 by way of the normally closed contacts controlled by the inner-lower armature of relay 422. This extension of the operating circuit, it will be noted, is made to the upper terminals of relay 421, whose lower terminal is connected to battery through the operating magnet 433. 80 Relay 421 is accordingly connected in series with the operating magnet 433 and relay 425, but is short-circuited at the armature of relay 425.

It will be noted that the ground potential 95 is removed at the lower armature of relay 428 from the spring combination controlled by the armature of line relay 424. This is done so as to prevent relay 425 from being short circuited upon the next deenergization 100 line relay 424.

Having dialled the required stations digits, the calling subscriber at substation A1 replaces his receiver to allow the ring-back process to take place. When this is done, relay 105 424 falls back and removes the short circuit from around relay 421. Relay 425 is now held operated in a circuit including its own inner-lower armature, inner-lower armature, operated, of relay 428, normally closed contacts 110 controlled by the inner-lower armature of relay 422, relay 421, and operating magnet 433. Relay 421 now operates in this holding circuit in series with relay 425 and at its lower armature places ground on the interrupter 115 start conductor 622; it connects the pick-up conductor 713 to pick-up relay 423 at its inner-upper armature, and at its two uppermost armatures it disconnects the incoming conductors 364 and 366 from the windings of line 120 relay 424 and connects them instead to the ringing circuit.

When the ringing interrupter of Fig. 7, which is started responsive to the grounding of interrupter start conductor 622 by relay 421, 125 arrives in its pick-up position and grounds the pick-up conductor 713, pick-up relay 423 operates through contacts of relay 421 and locks itself to ground through the inner-upper armature of relay 425, at the same time open- 130

ing its initial circuit. At the middle-upper armature of relay 423, a ground potential is applied to the lower left-hand repeating-coil terminal through contacts of relay 421, and at the upper contacts of relay 423 the connection is completed from conductor 364 through the lower winding of ring-cut-off relay 422 to wiper 440. At its three lower armatures, relay 423 connects up the first and third and fifth code conductors to the bank of the digit registers DR1 and DR2. These conductors are normally open so as to prevent sparking occasioned by the passage of the wipers of the digit register DR1 and DR2 from contact to contact.

The ringing current now sent back to the line of substation A1 depends upon the relative setting of the registers DR1 and DR2. In case the ringers of the calling and called stations are connected to opposite sides of the line, it is necessary to send out the code of the calling station on one side of the line in addition to sending out the code of the called station on the other side of the line so that the calling man will know, by the cessation of his code, when the called man has responded, but if both ringers are connected between the same side of the line and ground, it is necessary to send out only the code of the called substation, as this code is then heard at both substations. Assume, for example, that both ringers are connected between the upper line conductor and ground. In this case, the last two digits will be from one to five in both cases and the wipers of the digit registers DR1 and DR2 will be set on the first half of their contact banks. In this case, the position of wiper 440 directly determines the code sent to the line through the upper talking conductor, as it directly contacts with one of the five code conductors, while the wiper 441 extends the lower right-hand terminal of the repeating coil 431 by way of any one of the first five contacts in its banks to wiper 436. This terminal is not further extended by wiper 436, however, on account of the fact that the first five contacts in its bank are left dead.

If it is assumed that the ringer of the calling station is connected between the lower conductor of the line and ground, the stations digit assigned thereto is any one from six to 0, with the result that the dialling of this digit results in the digit register DR1 being set on a bank contact set of the second half. In this case, the wiper 436 extends the lower right-hand terminal of the repeating coil 431 to one of the code conductors. As a result, the code of the calling subscriber is sent back over the lower talking conductor, owing to the repeating action of the repeating coil 431, at the same time that the code of the called party is sent back over the upper conductor. It is the necessity for the simultaneous signalling over both conductors that gives rise to the repeating coil 431, which is

used in order that a battery potential may be present at all times on the lower talking conductor so as to form a circuit for the lower winding of the ring-cut-off relay 422 at any time that the receiver may be removed at any station on the calling line.

It will be noted that, in case the digit used to set the digit registers DR2 is any one from 6 to 0, the wipers 440 and 441 are set on the second section of the banks and it is the lower conductor upon which the ringing current is impressed by wiper 441 through the medium of the repeating coil 431, while whether or not ringing current is impressed upon the upper conductor by wiper 440 depends upon the specific setting of wiper 435. If the digit register DR1 is set on the second section of its bank, the wiper 435 merely encounters the ground potential for completing the circuit of the ring-cut-off relay and no ringing current passes out over the upper talking conductor, because both ringers are connected between the lower conductor of the line and ground and both the calling and the called party hear the code assigned to the called substation. On the other hand, if the calling substation is one whose ringer is connected between the upper line conductor and ground, the digit register DR1 is set in accordance with a digit from 1 to 5 and the upper conductor is extended to a code conductor by wiper 435 in the first half of its contact bank.

At any rate, the calling party hears his own code transmitted back to the calling line over the conductor to which his ringer is connected, and at the same time that the other code is transmitted back over the other side of the line, or else he hears only the code of the called substation in case both ringers are connected between the same side of the line and ground.

Assuming first that the called party does not respond, the calling subscriber removes his receiver and again replaces it in order to clear out the ringing equipment and cause the connection to be released in a manner to be hereinafter described.

Assuming now that the subscriber at the called substation responds, a circuit is completed for the lower winding of ring-cut-off relay 422 to ground by way of wiper 440 and one of the code conductors directly or through wiper 435 and one of the code conductors or through wiper 435 and ground directly. The return path for the operating circuit of relay 422 is to battery by way of the upper winding of repeating coil 431. Upon operating, relay 422 closes a locking circuit for its upper winding at its inner-upper armature through the inner-upper armature of release relay 425; it prepares again the shunt for relay 425 at its lower armature; and at its inner-lower armature it connects relay 426 (in parallel with operating magnet 438

through the inner-lower armature, operated, of relay 427) to the operating circuit in substitution of relay 421 and the operating magnet 433 in series. This leaves a holding circuit established for relay 425 through its own inner-lower armature, the inner-lower armature, operated, of relay 427 and the operating magnet 438.

Relay 421 falls back at this time and removes ground from the interrupter-start conductor 622 at its lower armature, at the same time short circuiting relay 425 through its lower armature and resting contact, corresponding armature of relay 422, middle-lower armature of relay 428, and the contacts of the armature of relay 424. The placing of this short circuit around relay 425 closes the usual operating circuit for relay 426 and the magnet 438. This operating circuit is usually opened, however, before the relay and magnet have had time to operate and in a manner to be now described: At its two uppermost armatures relay 421 transfers conductors 364 and 366 back to the windings of line relay 424, whereupon line relay 424 again operates and establishes the regular circuit for relay 425 in series with operating magnet 433, removing the short circuit from around relay 425.

The two subscribers may now converse with each other in the usual manner, the transmitters at the two substations being supplied with talking current through the windings of relay 424.

It may be pointed out that, in case the ring-back switch RB1 is used in connection with a connector or other first switch in the train which does not employ a dial tone, the jumper 429 is removed from between the associated terminals, with the result that, when ring-cut-off relay 422 operates, it removes ground from the holding conductor 365 and brings about the immediate release of the connection. The line switch LS1 of the calling line releases in that case and takes a new trunk line and the transmitter current is supplied from the line relay of the first switch of the train. In the present case, however, since dial tone is supplied to the calling line by the connector LC1 the jumper is left in place, as the dial tone would interfere with the conversation.

When the two subscribers replace their receivers at the end of the conversation, line relay 424 falls back and again short circuits release relay 425 through contacts of relays 428, 422, and 421 as above pointed out, incidentally operating relay 426 and the magnet 438. After an interval, relay 425 falls back and removes the holding ground from conductor 365 at its upper armature, opening the circuit of relay 426 and magnet 438 at its inner-lower armature. At its lower armature, relay 425 removes ground from the tone-start conductor and closes a circuit through

the associated shelf-supervisory relay for release magnet 434 of the digit register DR1 by way of the lower armature, operated, of relay 427. The magnet 434 operates and restores the digit register DR1 to normal position, whereupon off-normal contacts 432 open and cause the deenergization of relay 427. At the lower armature of relay 427 a circuit for the release magnet 439 is closed through the lower armature of relay 428. Release magnet 439 operates and causes the digit register DR2 to restore. Off-normal contacts 437 open and deenergize relay 428, which falls back and opens the circuit of release magnet 439 at its lower armature. The common release-signal relay is, of course, energized in series with either of the release magnets and falls back when the circuit of the last release magnet is opened.

In the local connector LC1, relay 321 falls back when the ground potential is removed from release-trunk conductor 365 of the ring-back switch RB1 and closes the release magnet circuit at its lower armature through contacts of relays 324 and 327. When this occurs, release magnet 336 operates and restores the connector to normal position in the usual manner.

Operation of the trunk-busy relays

The operation of the trunk-busy relays 402-404 will now be explained. It sometimes happens that a ring-back switch such as the ring-back switch RB1 becomes defective and does not operate properly, or that one of the conductors leading thereto becomes open. Since this ring-back switch is first choice to the several connectors, repeated attempts during light traffic to make a reverting call may all fail if the same ring-back switch is taken for use in each case. On the other hand, if there is an alteration so that the first call takes the first ring-back switch and a second call must take the second ring-back switch before the first is again rendered available for service, the second attempt to make a reverting call results in the second choice switch being taken for use over the conductors 367-369.

In order to accomplish this result of alternating between the first two ring-back switches, the relays 402-404 are provided, and they operate as follows: When the ring-back switch RB1 is taken for use and the release trunk conductor 365 is grounded, a circuit is closed through contacts of relay 402 for the slow-acting relay 403. Relay 403 operates and locks itself to ground at its inner-lower armature through contacts and winding of relay 402 and contacts of relay 404. This locking circuit does not become effective and no current flows through it as long as the ground potential is maintained on conductor 365. When, however, the ground potential is removed from conductor 365

upon the release of the connection, relay 402 operates in series with relay 403 and closes a locking circuit for itself through resistance 401, at the same time opening the circuit of relay 403. After a slight interval, relay 403 falls back and applies a guarding potential to conductor 365 at its lower armature through the lower armature of relay 402. The delay in the application of this guarding potential to conductor 365 is of sufficient interval to permit the connector involved in the connection to restore. With relay 402 operated and relay 403 restored, relay 404 is connected to the release trunk conductor 368 of the ring-back switch RB2 through contacts of relays 402 and 403.

When the next reverting call is made, the trunk line comprising conductors 367—369 leading to the ring-back switch RB2 is seized on account of the fact that the trunk line leading to the switch RB1 is made artificially busy, as above explained. When this trunk line is seized, relay 404 operates and opens the circuit of relay 402 whereupon relay 402 falls back and removes the guarding potential from the conductor 365 to permit the next call to come in to the ring-back switch RB1. It will be understood, of course, that there may be other ring-back switches in addition to the two shown, in which case one of the remaining switches is taken any time a reverting call is made when the first two are in use.

Call from the C. A. X. to the manual exchange

It will now be assumed that the subscriber at substation A1, Fig. 3, desires to converse with a subscriber whose line terminates in a manual exchange, a part of the equipment of which is shown in Fig. 1. It will be assumed further that the line switch LS1, upon operating when the receiver is removed at the calling substation, seizes the local connector LC1 in which case the connector LC1 is prepared for operation in the usual manner. When the first digit 0, of the number 01 assigned as the call number of the manual office, is dialled, the wipers 339—342 are raised opposite the tenth level of bank contacts, and wiper 343 contacts with the tenth associated bank contact. Wiper 343 also bridges from the ninth contact to the tenth contact, causing wipers 340 and 341 to be both grounded as in the case of a reverting call. Relays 328 and 329 are energized as before, and, as soon as relay 329 falls back at the end of the vertical movement, it completes the circuit for stepping relay 325 from the grounded wiper 341 through contacts of relay 328. The first rotary step is accordingly taken to advance the wipers 339—342 onto the first set of contacts in the tenth level and to cause the wiper 343 to disengage the vertical contact strip. The rotary movement continues beyond the first bank contact set or stops, depending upon

whether the first trunk line is busy or idle. It will be assumed that the first trunk line is idle and that the movement accordingly stops. In this case, the busy relay 327 falls back, as does relay 328, and relay 330 is energized through its lower winding as pointed out hereinbefore in connection with a call between substation A1 and substation A2. The energizing circuit at this time includes the test wiper 340, as before, and is completed now to battery over the first contact in the tenth level, test conductor 371, contacts of relay 262, release trunk conductor 209 of the incoming connector IC, upper armature, normal, of relay 224, the associated off-normal spring and its lower contact, and the lower winding of relay 221 to battery. Upon energizing over this circuit, relay 330 disconnects the operating conductor from the rotary magnet 338 at its inner-lower armature and extends it to the operating magnet of the code switch CS2 with the result that, when the calling subscriber dials the next digit 1, the code switch CS2 is operated to enable ringing current to be transmitted over the trunk line TL1 associated with the incoming connector IC.

In the incoming connector IC, relay 221 operates as a cut-off relay and disconnects conductors 208 and 210 from the portion of the talking circuit including the front and back-bridge relays 222 and 223, so as to clear the line for ringing current. With ground potential applied to conductor 209, a current flows through the upper winding of the electro-polarized relay 204, but the relay is not operated by either winding alone due to the design of the windings of the relay.

When the ringing current is applied to the wipers 339 and 342 of the connector it passes over conductors 370 and 372 to the right-hand windings of the repeating coil associated with the alarm circuit ALCKT. The ringing current is repeated into the left hand windings of the repeating coil, and passes over the conductors of the trunk line TL1 to the manual office and is again repeated through the repeating coil there and operates the ring-up relay 107 through contacts of the cut-off relay 106. Upon operating, the ring-up relay locks itself operated mechanically under the control of the cut-off relay as is common practice in connection with the ring-up and cut-off pair. The ring-up relay closes a circuit for the answering lamp 108.

When the operator notes the lighted condition of the answering lamp she inserts the plug of a cord circuit (not shown) into the line jack LJ, whereupon the sleeve relay 106 operates over the sleeve of the jack from a battery potential applied to the sleeve of the plug of the cord and mechanically unlocks the ring-up relay 107 and permits it to restore. At its upper armature, relay 106 removes ring-up relay 107 from the circuit,

and, at its inner-upper armature, it grounds the upper terminal of relay 104, closing a supervisory circuit over the trunk line TL1 to operate relay 205 of the alarm circuit 5 AL.CKT. through its lower winding. Upon operating, relay 205 bridges the lower winding of relay 204 around the associated condenser, closing a circuit over conductors 370 and 372 for operating the ring-cut-off relay 10 326 in the local connector LC1. When relay 326 is operated it connects up the back-bridge relay 322, whereupon the current flow in the lower winding of the electro-polarized relay assists the current flow in the upper winding 15 on account of the fact that conductors 370 and 372 are reversed between the bank multiple and the conductors 208 and 210 as shown. Upon operating, relay 204 shifts the connection to relay 205 so that the high resistance upper winding is included in series 20 with the low resistance lower winding. This decreases the current flow over the trunk line TL to such an extent that relay 104 is unable to operate and complete the circuit of 25 the supervisory lamp 109, which is prepared by relay 105, energized through the lower armature of relay 106.

The operator now converses with the calling subscriber and extends the connection to 30 the desired line in the usual manner.

When the ensuing conversation is terminated, the subscriber at substation A1 replaces his receiver whereupon the connector LC1 and the line switch LS1 release in the 35 usual manner and the ground potential is removed from conductor 371. When this occurs, relays 204 and 221 fall back. Relay 204 increases the current flow over the trunk line TL by shifting the connections of relay 205 40 back to normal, whereupon relay 104, Fig. 1, operates and closes a circuit for supervisory lamp 109 so as to cause the lamp to become lighted as a disconnect signal.

When the operator perceives the disconnect signal, she pulls down the connection, whereupon relays 104-106 fall back and relay 205, Fig. 2, falls back as a result of the opening of the circuit over the trunk line.

In the interval between the replacing of 50 the receiver by the subscriber at substation A1 and the pulling down of the connection by the operator, a circuit is closed for line relay 223 of the incoming connector IC with the result that the connector is prepared for 55 operation in the usual manner, but this operation is merely incidental and its chief function is to guard the trunk line from seizure in the C. A. X. as long as the operator has the connection up in the manual exchange. 60 The connector is restored to its normal condition when the relay 205 falls back.

Call from the manual office to substation A2

It will now be assumed that the operator 65 in the manual office receives a call to be com-

pleted to the line of substation A2 in the C. A. X. Assuming that the trunk line TL1 is idle, the operator may insert the calling plug of her cord circuit in use into the line jack LJ, resulting in the energization of relays 106 and 105 and the energization of relay 104 over the trunk line TL1. Lamp 109 becomes lighted as a supervisory lamp. 70

Relay 205, Fig. 5, operates over the trunk line TL1 in series with relay 104 and closes a circuit through the lower winding of the electro-polarized relay 204 and the associated repeating-coil windings for line relay 223 through contacts of relays 221 and 222. Upon operating, relay 223 closes a circuit for relay 224 through resistance 244 and vertical magnet 235. The resistance 244 is included in this circuit for a purpose to be explained hereinafter. Relay 244 operates and prepares the incoming connector IC for operation in a manner explained in connection with the local connector LC1 and in addition shorts-circuits the resistance 244 at its inner-lower armature. It may be pointed out at this time that the incoming connector IC and the code switch CS1 taken together are almost identical with the local connector LC1 and the code switch CS2, and that they differ only in slight details to be fully explained. For this reason it will be considered unnecessary to repeat the description of the operation of the incoming connector IC in all its details. 80

In the manual office, the operator inserts the plug of the dial cord DC into the dial jack DJ after she has taken the trunk line for use, and she proceeds to operate the calling device CD in accordance with the three digits in the number of the line of substation A2. 90

When the calling device CD is first turned off-normal, a circuit is completed through the off-normal contacts thereof and over the tip of the plug and jack for relay 101. Relay 101 disconnects the simplex leg of the trunk line TL1 from ground through relay 104 and connects it instead to ground through the ring contacts of the jack and plug and the impulse contacts of the calling device CD. As a result, each time the impulse contacts are opened on the return movement of the calling device CD the circuit of the repeating relay 205, Fig. 2, is opened. Relay 205 falls back a number of times corresponding to the digit dialled and repeats the interruptions produced in its circuit into the circuit of line relay 223. As a result of this vertical magnet 235 is operated in the manner described in connection with vertical magnet 335, Fig. 3, and the wipers 239-242 are raised opposite the desired level of bank contacts. 105

When the next digit is dialled, rotary magnet 238 is operated to advance the wipers 239-242 into engagement with bank contacts in which the line of substation A2 terminates, and, if the line is idle, relay 230 operates to seize the line and to extend the operating cir- 110 120 125 130

cuit to the operating magnet 254 of the code switch CS1.

When the stations digit is dialled, the code switch CS1 operates in the manner described in connection with the code switch CS2 with the result that the called line is signalled.

When the called subscriber answers, ring-cut-off relay 226 operates and removes the ringing current and completes the talking circuit. Back-bridge relay 222 operates at this time and reverses the incoming conductors 208 and 210 in regard to their connection with the windings of line relay 223, whereupon the electro-polarized relay 204 operates and gives answering supervision to the calling operator by causing relay 104 to fall back and open the circuit of supervisory lamp 109.

Upon perceiving the disconnect signal when relay 104 operates again under control of relay 204, which is, in turn controlled by back-bridge relay 222 when the called party hangs up his receiver, the operator pulls down the connection, whereupon relay 205 falls back and the connector IC and the code switch CS1 both release.

Certain points wherein the connector IC differs from the connector LC1 will now be explained. The off-normal spring located above relay 222 is for the purpose of guarding the connector IC from seizure by a connector such as the connector LC1 while the connector IC is releasing. At this time relay 224 is at normal, but the off-normal spring mentioned above is in engagement with its grounded upper contact, placing a guarding ground potential on conductor 209 by way of the upper armature of relay 224. When the normal position is reached, the said off-normal spring moves into the position shown in the drawing, rendering the connector idle.

Since the connector cannot release until the code switch CS1 releases and permits relay 227 to fall back, the connector is held guarded in case either it or the switch CS1 is unable to release.

The resistance 244 is provided to prevent a sufficient current flow through magnet 235 to cause eventual damage in case the conductor 208 becomes grounded just sufficiently to cause the armature of line relay 223 to move over against its contacts, but not enough to move it all the way. In this case relay 224 remains short circuited and resistance 244 is not shunted as it is when relay 224 operates.

With reference to the trunk busying relays 262-264, these relays operate in the same manner as relays 402-404, Fig. 4, in order to make the trunk line extending to the incoming connector IC artificially busy, after it has been used, until the trunk line TL2, which is the second trunk of the group, has been used.

It will be noted that the incoming connector IC has access to the ring-back switches of Fig. 4 and also to the trunk lines incoming

from the manual office along with the local connector LC1. The multiple is left intact between the incoming connector and the local connector LC1 on the ninth and tenth levels so that the operator in the manual office can test the ring-back switches and the manual-to-automatic trunk lines.

Giving trouble alarms

In case an abnormal condition arises with in the P. A. X., such as the failure of one or the other charges to start, the failure of the ringing machine, or the sticking of a connector in an off-normal position or the blowing of a fuse, it is necessary that an alarm be given or that the condition be indicated so that the defect may be remedied. In case the trouble consists in a fuse of a local connector being blown or the connector stuck in an off-normal position, there is no emergency existing and there is no need of sounding an alarm to get the same prompt action as would be required in case of the failure of the ringing current, for example. This difference in the importance of the various trouble conditions is recognized in the present disclosure in the division of alarms into two classes, regular alarms and emergency alarms.

The relays 551-555, Fig. 5, are the regular-alarm relays, and the relays 556-560 are the emergency-alarm relays. More in particular, relay 554 of the first group is the one which eventually operates in case there is a regular alarm existing, and relay 559 is the relay of the second group which operates to sound an emergency alarm. The way in which these relays are operated will be explained more in detail hereinafter. At this time it will be merely assumed that relay 554 operates to indicate a so-called regular-alarm condition such as the failure of a connector to release, in which case it closes a circuit at its lower armature for relay 562. Relay 562, upon operating, closes a circuit at its upper

armature for the local buzzer 531 which signals an attendant in case one is present, making a repair, for example. At its lower armature, relay 562 closes a circuit for relays 563 and 564 in series with the associated resistance. Relay 563 is normally short circuited by the contacts of relay 564 and relay 564 operates first and removes the short circuit from around relay 563. Relay 563 then operates and short circuits relay 564, causing relay 564 to fall back and again short circuit relay 563. This action continues with the relays 563 and 564 alternating. Each time relay 564 operates it opens the circuit that is normally closed through contacts of relay 561 from battery through resistance 565 and over conductor 547 to the normally energized relay 201 in the alarm circuit AL.CKT. When relay 201 falls back, it closes at its lower armature a circuit for the buzzer 202 in

series with the primary winding of the induction coil 203. The buzzer 202 starts operating at a predetermined, fixed frequency, short circuiting its winding each time the armature is pulled up and removing the short each time it is allowed to fall back. At its upper armature, relay 201 grounds the secondary winding of the induction coil 203 through the associated condenser, so as to cause the tone current to be placed on the midpoint of the left-hand repeating-coil winding. This tone current is thus projected over the trunk line TL1 and it causes the operation of the tuned relay 103, Fig. 1. This relay is tuned to respond only to the frequency at which the buzzer 202 operates. Upon responding, relay 103 opens the circuit of relay 102, whereupon relay 102 falls back and closes the circuit for the lamp 110 and for the buzzer 111, giving visual and audible indication of the alarm condition.

Each time the alarm circuit over conductor 547, Fig. 5, is reclosed by the deenergization of relay 564, relay 201 operates again and opens the buzzer circuit and the alarm circuit over the trunk so that an intermittent operation of the tuned relay 103 results, with a corresponding intermittent operation of the lamp 110 and the buzzer 111. This intermittent operation of the visual and audible signals indicates that the alarm being sounded is a regular alarm and not an emergency alarm.

Sounding an emergency alarm

It will now be assumed that the emergency alarm relay 559 operates whereupon it closes a circuit at its lower armature for relay 561. Relay 561 operates and opens the circuit over conductor 547 for relay 201, Fig. 2, at the same time closing a circuit for the local buzzer 531. This circuit remains open and the alarm current is sent over the trunk line TL1 continuously as long as the emergency alarm exists. The uninterrupted nature of the alarm given in this case indicates to the operator or other attendant in the manual office that an emergency alarm exists and the proper steps may be taken to clear up the trouble.

In case there is both a regular alarm condition and an emergency alarm condition, the emergency alarm signal only is given, as an operation of relay 564 does not have any effect on conductor 547 as long as relay 561 is operated.

The current supply system

Upon reference to the upper portion of Fig. 5, it will be observed that two batteries are provided, B1 and B2. The positive terminals of these batteries are joined together and grounded, while the negative terminals are connected together through the choke coil 508 so that when the battery B1 is being charged

the battery B2 receives a charge through the choke coil 508, while the voltage fluctuations delivered to the battery B1 by the charger are smoothed out and prevented from entering the battery B2. The current to the switching apparatus, such as that shown in Figs. 2, 3, and 4, is taken from the battery B1 by way of bus-bars 509 and 510, while the current to the power apparatus such as shown in the remaining part of Fig. 5 and Figs. 6, 7, and 8 is taken from the battery B1 by way of the bus-bars 511 and 512. Wherever a battery symbol appears in Figs. 2-8, one or the other of the batteries B1 and B2 is meant.

It will be observed that the leads extending from the ground-bus-bars 510 and 512 are not fused, while the leads extending from the ungrounded bus-bars 509 and 511 are provided with fuses. This is in accordance with standard practice. Furthermore, there is an alarm bus-bar arranged parallel to each battery-supply bus-bar, and the fuses furnished are such that when one blows a spring portion of the fuse contacts with the alarm bar so as to sound an alarm. It will be noted, for example, that the bus bar 509 is provided with an alarm bar 513 and another alarm bar 514. The alarm bar 513, it will be observed, is associated with the relay 556 of the emergency alarm group, while the bar 514 is associated with relay 551 of the regular alarm group. When one of the fuses associated with the alarm bar 513 blows and connects the bus-bar 509 to the bar 513, a circuit is closed for relay 556 in series with the signal lamp 538, whereupon relay 556 closes a circuit for relay 559. Relay 559, of course, operates and gives an emergency alarm in the manner hereinbefore pointed out. On the other hand, if a fuse blows associated with the alarm bar 514, a circuit is closed for relay 551 in series with the regular-fuse lamp 532. Relay 551 closes a circuit for relay 554 resulting in a regular alarm signal being given in the hereinbefore described manner. It will be noted that the same arrangements are employed in connection with the bus-bar 511 associated with the battery B1. That is, the emergency alarm bar 515 is provided for those fuses supplying current to main pieces of apparatus, such as the ringing equipment of Fig. 8, while the regular alarm bar 516 is associated with fuses supplying current to minor pieces of power apparatus, if any.

Charging the batteries B1 and B2

The arrangements for automatically charging the batteries B1 and B2 will now be described. Each time a local call is made, the master switch start relay 311, Fig. 3, operates momentarily and places ground on the master-switch signal conductor 541. This closes the circuit through the lamp 540, Fig. 5, for relay 557. Relay 557 operates and closes a circuit for the charge-starting relay 502. Re-

lay 502 operates and locks itself through the contacts of relay 501 at its inner-upper armature; it closes a circuit for relay 501 through the associated resistance at its lower armature; and at its upper armature it operates 5 the power relay 507 to complete the charging circuit from the commercial alternating current supply conductors 517 and 518. Relay 501 is adjusted so as to require the full 10 voltage of the battery under charge in order to operate. Accordingly, relay 501 does not operate when it is connected up by relay 502.

The chargers C1 and C2 each contain a tube, the tube 504 being in the charger C1 and 15 the tube 506 being in the charger C2. These tubes are of the two-element type with their filament current supplied from a section of the secondary winding of the transformer.

When the battery voltage has risen to the 20 predetermined height, relay 501 operates and opens the circuit of relay 502 at its upper armature, allowing relay 502 to fall back and open the circuit of relay 501 so that relay 501 falls back again. It will be observed that 25 relay 501, at its lower armature, shorts circuits the resistance in series with its winding. The lower armature closes with its associated contact before the armature proper of the relay moves sufficiently to press against the upper 30 contacts of the relay. This resistance-shunting arrangement is employed to increase the pull of the relay when the resistance is short circuited so that the locking circuit of relay 502 is definitely broken when relay 501 starts 35 to operate. When relay 502 falls back the charge is terminated by the falling back of relay 507.

While the batteries are being charged, relays 503 and 505 are operated in series with 40 the respective leads of the chargers C1 and C2. In case either of these relays fails to operate, a circuit remains closed in parallel with relay 507 through the lamp 539 for relay 557 so as to cause an emergency alarm 45 to be given.

Operation of the alarm relays

When a circuit is closed through the lower winding of relay 557, either through the master switch alarm conductor 541 or by the failure of one of the charge-indicating relays 503 or 505 to pull up, relay 557 operates and closes a circuit for the pendulum relay 560. Relay 560 operates its pendulum armature, 55 closing a circuit through contacts of relay 559 for relay 558. After a slight interval, relay 558, which is slightly slow to operate, operates and opens the circuit of relay 560 and closes a new circuit for the energized 60 relay 558 in series with relay 559. It will be observed that relay 559 is short circuited by relay 560 as long as relay 560 is in an operated condition. Relay 560 deenergizes when it is disconnected at the armature of 65 relay 558 and the flexible spring thereof vi-

brates back and forth due to the weight on the end and continues to vibrate for several seconds. It will be noted that the spring has a front contact and a back contact both of which are normally not engaged by the 70 spring. While the spring is vibrating, however, it touches the front and back contacts alternately, maintaining relay 559 short circuited during a sufficient portion of the time to prevent it from operating while the spring 75 is vibrating. When the amplitude of the vibration of the spring of relay 560 has attenuated to such an extent that it no longer touches its front and back contacts, relay 559 is no longer intermittently short circuited 80 and it operates in series with relay 558, but only in case relay 557 is still operated.

In case the alarm condition persists and relay 559 operates as above pointed out, it places the two windings of relay 557 in parallel at its upper contacts, thereby permitting sufficient current to flow through the circuit to light the lamp 539 or the lamp 540 as the case may be, so as to give a visual indication of the source of the trouble when 90 an attendant arrives. At its lower armature relay 559 closes a circuit for the relay 561 in the alarm group giving an alarm as herein-before explained, while at its inner-upper armature it opens a point in the initial circuit 95 of relay 558 through the contact of relay 560. This is done so that in case of erratic vibration on the part of the armature of relay 560, relay 559 will stay operated once it has been able to operate sufficiently to open its 100 inner upper contacts, even though the armature spring of relay 560 should slightly touch one or the other of the contacts one or more times subsequently. The result of the operation of the inner-lower armature of relay 105 559 will be explained hereinafter.

It will be noted upon inspection that the relays 552, 553, 554, and 555 of the regular alarm group correspond, respectively, to the relays 557, 558, 559, and 560 of the emergency alarm group. The above-named relays of the regular alarm group operate in the manner just explained in connection with the relays of the emergency alarm group.

Operation of the tone equipment

Referring now particularly to Figs. 6, 7, and 8, it will be observed that, when the tone-start conductor 621 (shown at the right in Fig. 6 and common to the switches of Figs. 2, 3, and 4) is grounded, a circuit is closed through the upper armature, normal, of relay 610 and over conductor 623 for the tone-start relay 809, Fig. 8. Relay 809 operates 120 and connects up the dial-tone and tick-tone conductors 811 and 812 at its two lower armatures, while at its inner-upper armature it closes an operating circuit for the interrupter relays 805 and 806, for the busy-tone relay 125 130

807, and for the dial-tone relay 808. These relays thereupon start to operate. Relays 805 and 806, in addition to being relays from the generation of the tick-tone are used for interrupting the busy-tone current. When the circuit is closed for it, relay 805 operates and closes a circuit for relay 806, whereupon relay 806 operates and short-circuits relay 805 at its upper armature. Relay 805 falls back and opens the circuit of relay 806, at the sametime short circuiting the relay. In this way, the two relays operate alternately and interrupt the busy tone current supplied to the busy tone conductor by relay 807, which relay is differentially wound, causing it to vibrate in a buzzer-like manner.

The openings and closings of the circuit of relay 806 causes impulses of current to be transmitted to the tick-tone conductor 812 through contacts of relay 809 and the associated condenser. This tick-tone is not used in connection with the switching apparatus of the present disclosure, but is used in connection with other systems employing the same power apparatus. It will be noted that dial-tone relay 808 is similar to the busy-tone relay 807 and that it is also differentially wound so that it will operate in a buzzer-like manner, as a closure of the circuit through the upper winding results in an operation of the relay to place the lower winding in parallel with the first and cause the relay to deenergize. The principle distinction between the busy tone and the dial tone is that the busy tone is an interrupted tone whereas the dial tone is an uninterrupted tone.

As a further result of the above-pointed-out energization of relay 809, a circuit is closed at armature 823 for the right-hand windings of the differentially-wound horse-shoe magnet 804 of the ringing interrupter 802. When magnet 804 energizes, it attracts the weighted spring to the right, whereupon a circuit is closed for the left-hand windings of magnet 804. The left-hand windings neutralize the right-hand windings, with the result that the spring 803 is released and permitted to swing to the left and open the circuit. This action is repeated at a rate determined by the length of the spring and the mass of the weight. The spring 803 is arranged and proportioned to vibrate at the frequency of the usual ringing current employed in telephone systems. Each time it swings to the right, the spring 803 closes a circuit through armature 822 for the lower-left-hand winding of the ringing current transformer 801, and each time it swings to the left it closes a circuit through armature 821 for the lower right-hand winding of transformer 801.

As a result of the intermittent energization of the lower windings of transformer 801, the usual form of ringing current is generated in the upper winding of the transformer 801 and

is delivered over conductor 813 to the code-ringing relays 721-725, Fig. 7.

Operation of the ringing interrupter

Referring now particularly to Fig. 7, the operation of the ringing interrupter comprising relays 701-710 will be explained. This interrupter is started into operation when the interrupter-start conductor 622, Fig. 6 is grounded by the switching apparatus, such as is shown in Figs. 2 and 4. The interrupter-start conductor normally extends through contacts of relay 610 to the ringing interrupter of Fig. 7, by way of conductor 624.

When conductor 624 is grounded, a circuit is closed for relay 701 of the interrupter pair comprising relays 701 and 702, and through the associated resistance to battery. Relay 701 operates and closes a circuit for relay 702 from the grounded conductor 624, but relay 702 does not operate immediately owing to the fact that the contact of the armature 701 is provided with a weighted spring as shown, which causes the contact to vibrate back and forth a few times before it allows the circuit of relay 702 to become permanently closed. When the contact of relay 701 ceases to vibrate, relay 702 operates and opens the circuit of relay 701, at the same time closing a local circuit for the winding of the relay so as to render it slow to release. Relay 701 falls back after a slight interval and again opens the circuit of relay 702. Relay 702 then falls back and again closes the circuit of relay 701. This cycle of operation is repeated over and over as long as conductor 624 remains grounded.

The remaining relays 703-710 of the interrupter are the counting relays controlled from relay 702. These latter relays respond to the successive operations of relay 702 and arrange themselves successively in each of the fifteen positions of the device.

When relay 702 operates the first time, it closes a circuit at its lower armature through the unoperated armatures of relays 710, 708, 706, and 704 for relay 703. Relay 703 operates and locks itself in series with relay 704. Relay 704 does not operate for the time being on account of the fact that it is short circuited by the initial circuit for relay 703.

When relay 702 falls back and opens the initial circuit of relay 703, relay 703 remains operated in series with relay 704 and relay 704 immediately operates.

When relay 703 first operates and until relay 704 operates, the counting device is in position 1, but when relay 702 falls back and permits relay 704 to operate the counting device is in position 2.

As a result of the operation of relay 704 the operating circuit is disconnected from the first pair of relays and is transferred to relay 705. As a result relay 705 operates and brings the device in the position 3 upon the

next operation of relay 702 and relay 706 operates in series with relay 705 when relay 702 again falls back.

In a similar way, relays 707 and 708 respond to the next operation and deenergization of relay 702, and relays 709 and 710 respond to the next operation and following deenergization of relay 702.

By the time relay 710 operates the device is 10 in position 8, with all the relays operated. The next step is to successively deenergize all the relays. Accordingly, at its inner-lower armature, relay 710 disconnects the lower armature of relay 702 from the operating circuit and at its upper armature relay 710 extends a battery potential to the upper contacts of relay 702. Therefore, when relay 702 energizes again, it extends the battery potential through the inner armature of the operated 15 relay 704 to the junction of relays 703 and 704, short circuiting relay 703. Relay 703 immediately falls back, and the device is in position 9.

When relay 703 falls back relay 704 is held 20 up to the upper contact of relays 702 and 710. As a result, when relay 702 falls back, relay 704 falls back also and the device is in position 10.

In a similar way, the next energization and 25 deenergization of relay 702 results in relays 705 and 706 falling back; relays 707 and 708 fall back on the next energization and deenergization of relay 702; while relays 709 and 710 fall back on the following energization 30 and deenergization of relay 702.

With all the relays again deenergized, the device is again in normal position and the subsequent energizations and deenergizations of relay 702 cause the counting relays to repeat 35 the above operations.

In order to enable the operation to be remembered best, the notation, "1, 3, 5, etc." is placed adjacent relay 702. This indicates that relay 702 is energized in the odd-numbered 40 positions of the device. It will be noted that the indication "1—8" is placed just above relay 703. This means that relay 703 energizes at the beginning of position 1 and remains energized continuously until the 45 end of position 8 when it falls back. Similarly, it is indicated that relay 704 is energized in positions 2—9. That is, from the beginning of position 2 to the end of position 9. In a similar way, the positions in which the 50 remaining relays are energized have been indicated, and it will be noted that the last relay, relay 710, is energized from the beginning of position 8 until the end of position 15. It may be pointed out that each relay is 55 energized through eight positions.

The interrupter relays 721—725 are energized through the contacts of the relays 704 to 710, and also through the lower contacts of relay 702. The positions of the device in 60 which the relays 721 to 725 are energized is

indicated in each case just above the relay. For example, relay 721 is energized at the beginning of position 8, and remains energized until the end of position 10. The relay is initially energized when relay 710 pulls up 70 at the beginning of position 8, and it falls back when relay 705 falls back at the end of position 10.

Conductor 715, through which the energization of relay 721 is effected, is used also to 75 supply current to conductor 716 and it is indicated that conductor 715 is grounded from the beginning of position 8 to the end of position 15. This will be apparent when it is noted that this conductor is grounded throughout the entire time that relay 710 is energized.

Conductor 716, it will be noted, is grounded in positions 11—14, and a ground potential is accordingly extended to relay 722 to 80 energize it in positions 11—14 through contacts of relay 705, after relay 722 has been energized in position 9 through the contacts of relay 702, inner-lower armature of relay 710, and the lower armature of relay 704.

A reference to the chart shown in Fig. 11 85 will be of assistance in determining the codes transmitted over code conductors 1—5 by the relays 721, 723, 724, 725, and 722, respectively. It will be seen from the chart that code 1 consists of one long ring sent out in positions 8—10; that code 2 consists of two short rings sent out in positions 9 and 11; that code 3 consists in three short rings sent out in positions 9, 11, and 13; that code 4 consists in 90 four short rings sent out in positions 9, 11, 13, and 15; and that code 5 consists in a short ring sent out in position 9 and a long ring sent out in positions 11—14.

In order to insure that the ringing following the setting up of a connection does not start during the code transmission, but starts only between the transmission of successive codes, the pick-up conductor 713, which is used to operate pick-up relay 231, Fig. 2, and pickup relay 331 of Fig. 3, is grounded only between successive codes. It will be noted that, when relay 707 operates in position 5, ground is placed on the pick-up conductor 713 and that it is removed at the end of position 6 when relay 709 operates. This means that the pick-up conductor is grounded only through positions 5 and 6 while there is no application of ringing current being made.

Automatic testing of ringing equipment

In order that the C. A. X. shall be able to give service in spite of a failure of the ringing equipment of Figs. 7 and 8, a duplicate of the equipment of Figs. 7 and 8, with the exception of the transformer 801 and the associated condensers, is provided. The conductors which are common to the two sets of equipment have common connections indi- 125 130

cated thereon in the usual manner. These conductors include, for example, the busy-tone and dial-tone conductors and the ring-current-supply conductor of Fig. 7.

Relay 610 of Fig. 6 is provided to transfer the tone-start and interrupter-start conductors 621 and 622 from conductors 623 and 624 (extending to Figs. 8 and 7, respectively) to the corresponding conductors 623' and 624' extending the spare set of equipment. Other apparatus of Fig. 6 is arranged to bring about the operation of relay 609 at the proper time and also to cause an emergency alarm to be sounded in case the spare set fails to operate. The way in which this is done will now be pointed out:

When the interrupter-start conductor 622 is grounded to start the operation of the ringing interrupter in Fig. 7, a circuit is closed through the upper contacts of relay 609 and through the inner-upper contacts of relay 607 for the pendulum relay 608. Relay 608 is similar to relays 555 and 560, hereinbefore described. Upon operating, relay 608 closes a circuit through contacts of relay 607 for relay 606. Relay 606 operates and at its lower armature closes a locking circuit for itself independent of the contacts of relay 607, at the same time closing a circuit for relay 607 at its upper armature. Relay 607 operates and opens the circuit of the pendulum relay 608. When relay 608 de-energizes, the pendulum swings back and forth and breaks the circuit of slow-acting relay 606 during each movement, but it maintains the circuit closed enough of the time to maintain relay 606 operated for the time being. Relay 606, accordingly, remains operated for several seconds while the pendulum of relay 608 is vibrating.

When the pendulum of relay 608 ceases to vibrate with sufficient amplitude to send impulses to relay 606, relay 606 falls back and opens a point in its locking circuit at its lower armature, and at its upper armature opens the circuit of relay 607. Relay 607 falls back after an interval and again energizes relay 608. Following this, relays 606 and 607 both energize again and relay 608 is deenergized to permit its pendulum to again swing. It will thus be seen that this cycle of operations is repeated over and over as long as the circuit from the interrupter start conductor 622 remains closed through the contacts of relay 609 to the relays 606—608.

Relay 606 is so timed that it takes longer for the relays 606—608 to go through its cycle of operation than it takes for the ringing interrupter of Fig. 7 to complete a cycle of operation. As a result, between two successive operations of relay 608, the ringing interrupter of Fig. 7, if it is operating properly, has gone through a complete cycle of operation. Accordingly, conductors 711 and

712 have both been grounded. Conductor 712 is grounded at the beginning of position 7 and remains grounded until the end of position 8, and conductor 711 is grounded from the beginning of position 9 until the end of position 14.

When conductor 712 is grounded with relay 607 operated, a circuit is closed through the inner-upper contacts of relay 607 for relay 605. Upon operating, relay 605 closes a locking circuit for itself at its upper armature and opens its initial circuit.

When conductor 711 is grounded by the ringing interrupter of Fig. 7, a circuit is closed through contacts of relays 603 and 607 for relay 604. Relay 604 operates and closes a locking circuit for itself at its upper armature, opening its initial circuit. Relay 603 is operated over conductor 813 by ringing current.

It will thus be seen that relays 604 and 605 are both operated ordinarily when relay 606 falls back at the end of the cycle of the above-described operations of relays 606—608.

In case one, or both, of the relays 604 and 605 fails to operate (either due to the fact that the ringing machine 802 is not operating or the ringing interrupter of Fig. 7 is not operating), when relay 606 falls back and opens the circuit of slow-acting relay 607 at its upper armature, it closes a circuit through the back contact of its upper armature and through the lower contacts of one or both of the relays 604 and 605 for the lower winding of relay 611, by way of the lower contacts of the still-operated relay 607 and the inner lower armature of relay 610. Upon operating, relay 611 closes a locking circuit for itself at its upper armature through contacts of relay 612 and the winding of relay 610. As long as its initial circuit is closed, the locking circuit of relay 611 is without affect and no current flows through the winding of relay 610.

When relay 607 falls back after an interval and opens the initial circuit of relay 611 at its lower armature, relay 610 energizes in series with relay 611 and prepares a circuit for relay 609, at its inner-lower armature. At its two upper armatures, relay 610 disconnects the tone-start conductor 621 and the interrupter-start conductor 622 from conductors 623 and 624 and connects them instead to the conductors 623' and 624' of the spare set of tone and interrupter equipment.

In case the spare set functions properly, relays 604 and 605 are both operated by the time relays 606—608 have gone through another cycle of operations. However, in case the spare set fails to operate properly, one or both of relays 604 and 605 fails to operate, and, when relay 606 falls back, it closes a circuit for relay 609, relay 610 having been operated. When relay 609 operates, it closes a circuit at its upper contacts for the still-

operated relay 607 so as to maintain relay 607 operated and stop the operations of relays 606—608. Relay 609 also closes its own circuit locally through contacts of relay 611 and opens its connection with the interrupter start conductor 622. Accordingly, relay 609 remains operated from a local source as long as the spare set is not functioning properly.

In case the spare set subsequently starts to function properly, relays 604 and 605 both operate, and the circuit of relay 609 is broken. Relay 609 thereupon falls back and the testing operation of relays 606—608 is resumed.

It will be observed that when relay 610, which is the relay that transfers the tone-start and interrupter-start leads from the register set to the emergency set, is operated it grounds conductor 546 at its lower armature, bringing in a signal through the ringing machine lamp 537, Fig. 5, on the regular alarm equipment. This results in the eventual operation of relay 554 to close a circuit at its lower armature for relay 562, to give the regular alarm.

It will be observed that when relay 609 operates as hereinbefore described, when the spare set is connected up but fails to operate, a circuit is closed at the lower contacts of relay 609 over conductor 543 for operating relay 559 in the emergency alarm group. Relay 559, as before explained, brings in an emergency alarm by operating relay 561 at its lower armature.

Supervising the C. A. X.

Arrangements have been provided in the C. A. X. whereby the operator can take a trunk line, such as the trunk line TL1 for use and operate an incoming connector, such as the incoming connector IC, Fig. 2, to discover the condition of the exchange. This expedient may be resorted to at any time that there may be reason to suppose that the arrangements for transmitting the alarms over the trunk line TL1 by way of the alarm circuit shown in the left hand part of Fig. 2 is out of order. For this purpose, the trunk line TL1 is taken for use by the operator in the hereinbefore described manner through the equipment shown in Fig. 1, whereupon the incoming connector IC of Fig. 2 is prepared for operation in the usual manner.

The operator next dials the number 856, causing the wipers 239—242 of the incoming connector IC to be raised opposite the eighth level of bank contacts and to be rotated into engagement with the fifth set of bank contacts in the eighth level. This set of bank contacts is the first of the three sets shown in the lower right hand corner of Fig. 6, the wipers 239—242 of the incoming connector IC, Fig. 2, are also shown in this drawing.

When the wipers 239—242 contact with the respective contacts in set 85, the usual circuit 65 to battery over test wiper 240 is closed

through the resistance shown below relay 602, so as to afford a circuit for the lower winding of relay 230. Relay 230 prepares the code switch CS1 to receive the last digit 6, which sets the code switch CS1 and enables relay 231 70 to pull up over the pick-up conductor 713.

When the ringing circuit is thus closed by the operation of relay 231, a circuit is completed for the lower winding of ring-cut-off relay 226 by way of the upper wiper 239 of 75 the incoming connector IC to ground in series with relay 602 through the lower contacts of relay 601. Upon operating, the ring-cut-off relay 226 extends a connection through to the back-bridge relay 222, and the 80 back-bridge relay 222 may operate in series with relay 602. Whether the back-bridge relay 222 operates or not is entirely immaterial because its circuit is soon opened as will now be pointed out: When relay 602 operates 85 in series with the ring-cut-off relay it closes a circuit for relay 601, but relay 601 does not respond immediately on account of the slight amount of time required for the weighted contact of relay 602 to cease to vibrate after 90 it is struck by the armature spring. Relay 601 allows sufficient time for the ring-cut-off relay 226 to operate before it responds. When it operates, relay 601 locks itself to the ground potential supplied over test wiper 240 95 at its inner armature and disconnects the associated resistance, and at its lower armature it disconnects the conductor extended from the contact of wiper 239 from relay 602 and extends it by way of conductor 545 to the #3 100 code conductor by way of contacts of the emergency alarm relay 559 and contacts of the regular alarm relay 554. In case neither of these alarm relays is operated, the characteristics tone produced by the #3 code from 105 the relay 724, Fig. 7, is heard by the operator. However, if a regular alarm exists relay 554 is operated and the tone produced by code #1 is heard instead, while if an emergency alarm exists, the circuit is entirely open at the middle lower armature of relay 559 and no tone is heard.

Remote control of the ringing equipment

It will now be described how the operator in 115 the manual exchange can switch the ringing machines into and out of service. It will be assumed that the ringing equipment shown in Figs. 7 and 8 is operating, in which case relay 610 and 611 of Fig. 6 are deenergized. 120 With the apparatus in this condition, it will be assumed that the operator decides to substitute the spare set of equipment assumed to be connected to conductors 623' and 624' for the equipment shown in Figs. 7 and 8 and 125 connected to conductors 623 and 624. In order to do this, the operator takes an incoming connector for use over a trunk line in the usual manner, for example the incoming connector IC of Fig. 2 and sets the wipers 130

239—242 thereof onto the seventh set of bank contacts in the eighth level (see the lower right hand corner of Fig. 6). When wiper 240 lands on the eighty-seventh contact in its bank, a circuit is closed from ground through wiper 240 and the bank contact on which it is standing for the upper winding of relay 611 by way of the inner-lower armature of relay 611. Upon operating, relay 611 first closes a locking circuit for itself through its lower winding and the winding of relay 610 at its upper contacts, and then opens its initial circuit at its inner-lower armature. Relay 610 energizes in series with the lower winding of relay 611 and transfers the tone-start and interrupter-start leads 621 and 622 at its upper armatures.

In case the operator wishes to switch from the spare set to the regular set, she causes the connector to be set on bank-contact set 86, closing a circuit through the lower armature operated of relay 611 for relay 612. Relay 612 operates and releases relays 610 and 611 at its upper armature. In case relay 609 is operated, it falls back when it is disconnected by relay 610. When the operator causes the incoming connector to release, relay 612 falls back and again prepares the locking circuit for relays 610 and 611.

In case the operator dials the number 86 to set the incoming connector IC on the sixth set of bank contacts in the eighth level (shown in Fig. 6) at a time when relays 610 and 611 are already deenergized, the conductor connected to the contact engaged by wiper 240 is not connected to the releasing relay 612 but is instead connected to ground through the lower armatures of relays 611 and 612, causing a busy tone to be placed on the incoming trunk line by the usual action of the busy relay of the incoming connector.

In case the operator dials the number 87 at a time when relays 610 and 611 are operated and the spare set is in use, the bank contact encountered by test wiper 240 is grounded at the inner lower armature of relay 611 and the operator receives a busy tone.

The harmonic ringing system

Referring now particularly to Figs. 9 and 10, the operation of the improved P. A. X. when harmonic ringers are employed on the party line will now be explained. The power equipment such as is shown in Figs. 5 to 8 of the layout hereinbefore described is practically unchanged, except for the ringing apparatus which is of the harmonic type. The ringing equipment is shown diagrammatically in the lower left-hand corner of Fig. 10 and includes the five generators, each generating a different frequency; the interrupter 1063 driven by the motor 1061; and the interrupting relay 1062 which supplies interrupted current to the banks of the code selectors, such as the code selector CS3 associated

with the local connector LC2, Fig. 9. The interrupter-start conductor 1060 leading to the motor 1061 may correspond to conductors 624 of Figs. 6 and 7.

The generators, indicated conventionally, they may be, in practice, separate transformers, each of which receives impulses from a tuned interrupter similar to the interrupter 802 of Fig. 8, in which case they are all started responsive to the grounding of a conductor similar to conductor 623 of Figs. 6, 7, and 8.

The various conductors of Figs. 9 and 10 which correspond to those leading to the power and supervisory circuits in the layout including Figs. 1 to 8, have the same numbers applied in Figs. 9 and 10, except that each reference numeral is primed in Figs. 9 and 10. These conductors are 541', 534', 621', 622', 810', and 811'.

The apparatus shown in Fig. 9, including the substations A3 and A4, the local connector LC2 and the code switch CS3, is identical with that shown in Fig. 3 with the following exceptions: Harmonic ringers are used at the substations in the layout of Fig. 9 and there is no relay in the connector LC2, Fig. 9, corresponding to the pick-up relay 331 of Fig. 3. No pick-up relay is required when harmonic ringing is used. The function performed by the upper and lower armatures of relay 331, Fig. 3, has been taken over by similar armatures on the combination busy and ring starting relay 927, Fig. 9. The other portions of the connector LC2 have been given numbers to correspond with the similar portions of the connector LC1, except that the nine hundred series is used in Fig. 9, whereas the three hundred series was used in Fig. 3. In this way, the two connectors may be readily compared. For this reason it is thought unnecessary to explain the operation of the connector LC2 in detail.

The ring-back switch RB3, of Fig. 10, although similar in many respects to the ring-back switch RB1, of Fig. 4, is quite different because, when harmonic ringing is used, the calling and called parties must be signalled alternately when they are on the same side of the line, as one ringer does not respond to the frequency employed for operating the other ringer. This is distinct from the arrangement in Figs. 3 and 4, wherein code ringing is employed.

Making a reverte call in the harmonic system

In order to explain the operation of the ring-back switch RB3, it will be assumed that the subscriber at substation A3, Fig. 9, desires to converse with a subscriber at another substation on the same line.

When the receiver is removed at substation A3, the lineswitch LS2 operates in the manner described in connection with the line-

switch LS1 and seizes a local connector, such as the local connector LC2. When the connector LC2 is seized, the line and release relays 923, 924, and 926 operate in the manner described in connection with the local connector LC1, preparing the local connector for operation in the usual manner.

When the ring-back digit 9 is dialled, the wipers 939—942 are raised opposite the ninth level of bank contacts, whereupon the ninth-level shaft spring 935 is shifted to prepare relay 921 to operate, and the wiper 943 bridges across the eighth and ninth vertical contacts, causing the local connector LC2 to automatically rotate the wipers 939—942 in on the ninth level of bank contacts. It will be assumed that the trunk line comprising conductors 964—966 and extending to the ring-back switch RB3 is idle, and that it is, therefore, taken for use. The circuit completed over test wiper 940, in this case, includes resistance 1031.

When relay 921 pulls up in series with resistance 1031 and extends the incoming conductors through the wipers 939 and 942 to conductors 964 and 966 leading to the ring-back switch RB3, line relay 1025 of the ring-back switch RB3 operates and closes a circuit for release relay 1026 in series with the operating magnet 1033 of the digit register DR3. At its upper armature, relay 1026 disconnects the incoming release trunk conductor 965 from resistance 1031 and connects it to ground, so as to afford a holding circuit for the local connector LC2 and the line-switch LS2. At its inner-lower armature, relay 1026 closes a locking circuit for itself and prepares an operating circuit for magnet 1033, and at its lower armature it opens a point in the release circuit and extends ground through the associated low-resistance release-ground relay to the tone-start conductor 621.

When the calling subscriber dials the digit suffix assigned to his own substation, line relay 1025 falls back a plurality of times, and, each time it does so, it closes a circuit for the operating magnet 1023. This circuit includes the normally-closed contacts controlled by armature 1043 of relay 1022, the normally-closed contacts controlled by the armature of line relay 1025, inner-lower armature of release relay 1026, inner-lower armature, normal, of relay 1029, and the inner-lower armature, normal, of relay 1028. By the operation of the operating magnet 1023, the wipers 1035 and 1036 are advanced onto the bank contact set corresponding to the designation of the calling substation. Relay 1027 operates in parallel with operating magnet 1023 when the first impulse of current is delivered and it remains operated throughout the digit.

When relay 1027 falls back, the off-normal contacts 1032 of the digit register DR3 have

been closed, and a circuit is, therefore, closed at the upper armature of relay 1027 for relay 1028. Relay 1028 operates and locks itself at its upper armature, and at its inner-lower armature shifts the operating circuit from magnet 1033 to the operating magnet 1038.

When the calling subscriber dials the station suffix of the called substation, the impulses are delivered to magnet 1038 of DR4 with the result that the wipers 1040 and 1041 are positioned in accordance therewith.

When relay 1027 falls back at the end of the last digit, a circuit is closed for relay 1029 through the off-normal contacts 1037 of the digit register DR4. Relay 1029 operates and locks itself at its upper armature, and at its inner-lower armature disconnects the operating circuit from magnet 1038 and extends it through the normally-closed contacts controlled by the lower armature of relay 1021 to relay 1022.

When the calling subscriber replaces his receiver after having dialled the required digits, line relay 1025 falls back and again closes the operating circuit which is now extended to relay 1022. As a result, relay 1022 operates and grounds the interrupter-start conductor at armature 1044; and, at armature 1043 it disconnects ground from the operating circuit, removing the shunt from around release relay 1026. Relay 1026 now remains energized in series with relay 1022. At its upper armatures, relay 1022 disconnects the incoming conductors 964 and 966 from the windings of relays 1025 and extends them to the wipers of the digit registers DR3 and DR4 by way of the upper armatures of reversing relay 1024.

With the interrupter-start conductor 622 grounded, the ground potential is extended through a transfer circuit (such as that shown in Fig. 6 in connection with the upper armature of relay 610) to the interrupter start conductor 1060, corresponding to conductor 624 of Fig. 6. The motor 1061 now rotates the arm of the interrupter 1063 over the six associated conducting segments. One segment crossed by the grounded arm is connected to the ringing interrupter relay 1062 with the result that relay 1062 intermittently connects ringing current of the several frequencies to the conductors extending to the code switches such as the code switch CS3, Fig. 9. The operation of relay 1062 is merely incidental at this time.

Alternate segments of the interrupter 1063 are connected to the reversing conductor 1064, which conductor is now connected through the inner-lower armature of relay 1022 to the reversing relay 1025. Relay 1025 accordingly energizes and deenergizes under the control of the interrupter 1063. With the relay 1025 deenergized, conductors 964 and 966 are extended to the wipers 1040 and 1041 of the digit register DR4 and the frequency

130

assigned to the called station is sent out to the calling line over the conductors to which his ringer is connected, as determined by the position of the wipers 1040 and 1041. For example, if the wipers 1040 and 1041 are sent in the first half of the bank, the ringing current is transmitted out over the wiper 1040, while wiper 1041 merely connects to battery through the resistance 1042 so as to form a return circuit for operating the ringing-trip-control relay 1023 in case the called subscriber responds while relay 1024 is in a deenergized condition.

Each time conductor 1064 is grounded by the wiper 1063, relay 1024 energizes and disconnects the incoming conductors from the wipers 1040 and 1041 and connects them instead to the wipers 1035 and 1036 of the digit register DR3. The digit register DR3, it will be recalled, is set in accordance with the frequency and connection of the ringer at the calling substation. Accordingly, the frequency corresponding to the ringer at the calling substation is set out over the conductor to which the ringer is connected. This current is sent out over the conductor 964 by way of wiper 1035 if the digit register DR3 is set in accordance with a digit from one to five, and is sent out over the lower conductor 966 in case the digit register DR3 is set in accordance with a digit from six to naught. In either case, one or the other of the wipers 1035 and 1036 is standing on a bank contact connected to battery through resistance 1042 to furnish a return circuit for operating the control relay 1023 when the called subscriber responds.

When the receiver is removed at the called substation on the calling line, a circuit is closed for relay 1023 from ground through one of the harmonic generators shown in the lower left-hand corner of Fig. 10 over the calling line to battery by way of resistance 1042. Upon operating, relay 1023 closes a circuit for relay 1021 and relay 1021 operates and locks itself to the release trunk conductor, which is grounded at the upper armature of release relay 1026. At its lower armature, relay 1021 disconnects relay 1022 and short-circuits relay 1026 by substituting a ground potential. Relay 1022 falls back and at the armature 1043 places a new short circuit on relay 1026, at the same time opening the one just closed by relay 1021.

At armature 1044, relay 1022 removes ground from the interrupter-start conductor 622', and at its upper armature it transfers the incoming conductors 964 and 966 back to line relay 1025. Line relay 1025 operates and again closes a circuit for relay 1026 through the operating magnet 1023 before the short-circuited relay 1026 has had time to fall back.

The conversation may now take place between the two subscribers.

The ring-back switch RB3 releases in the usual manner when the receiver is replaced at both substations. Specifically, relay 1026 is short circuited and falls back when line relay 1025 falls back, and at its lower armature it closes a circuit over the release ground conductor for the release magnets 1034 and 1039 through contacts of relays 1028 and 1029. When both digit registers DR3 and DR4 have released, relays 1028 and 1029 fall back and open the circuit of the release magnet.

With regard to the trunk busying relays 1001—1004 associated with the ring-back switch RB4, reached by way of conductors 967—969, these relays operate in the manner described in connection with similar relays shown in Fig. 4.

What is claimed is:

1. In a telephone exchange wherein abnormal conditions are automatically indicated and wherein the abnormal conditions are classified in accordance with their importance, a conductor over which a current flow is normally maintained, means responsive to an abnormal condition of one importance for intermittently interrupting the current flow over said conductor, and means responsive to an abnormal condition of a different importance for stopping the current flow over said conductor as long as such condition persists.

2. In a telephone exchange wherein indications of abnormal conditions are automatically given and wherein abnormal conditions are classified in accordance with their importance, a signal conductor over which indications of abnormal conditions are given, means responsive to an abnormal condition of one importance for causing current to flow intermittently over said conductor, and means responsive to an abnormal condition of a different importance for causing current to flow continuously over said signal conductor.

3. In a telephone exchange system wherein indications of abnormal conditions within a telephone exchange are transmitted to a distant point, a telephone line extending between said exchange and the distant point, and means for indicating the abnormal conditions at said distant point controlled by a current flow in a circuit including the two sides of said telephone line in parallel and a separate return conductor.

4. In a telephone exchange system wherein indications of abnormal conditions within a telephone exchange are transmitted to a distant point, a telephone line extending between said exchange and the distant point, means for indicating the abnormal conditions controlled by a current flow in a circuit including the two sides of said telephone line in parallel and a separate return conductor, and means for transmitting impulses over the two sides

of said telephone line in parallel and a separate return conductor to control switching apparatus in said telephone system.

5. In a telephone system wherein abnormal conditions arising within a telephone exchange are indicated at a distant point by sending current from the exchange over a telephone line to said distant point, means in said telephone exchange responsive to an abnormal condition for transmitting current impulses of a fixed frequency over said telephone line to said distant point, and a receiving relay at said distant point tuned to respond to impulses of the same frequency so as to avoid its responding to foreign disturbances on the telephone line, and means at the said distant point responsive to operations of said tuned relay to indicate abnormal conditions arising in said telephone exchange.

10. 6. In a telephone exchange system wherein indications of abnormal conditions arising within an exchange are indicated at an outside point by current flow over a circuit extending from the telephone exchange to said outside point, said current flow being from a current generator within said exchange, and means responsive to an abnormal condition within said exchange for operating said current generator to set up a current flow over

15. 7. In a multi-exchange telephone system, a trunk line incoming to an exchange and terminating in a connector switch having access to subscribers' lines, said trunk line being accessible on the incoming end to the other connectors, means responsive to the taking of said trunk line for use at the originating end for operating a relay at the incoming end to guard the trunk line from seizure by the other connectors, said incoming connector being operable over said trunk line to extend connections, and additional means in said incoming connector for guarding the trunk from seizure as long as it is in an off-normal

20. 45. condition whether the trunk line is under a condition of seizure or not.

8. In an automatic switch wherein a release relay is operated through contacts of the line relay on the energization of the latter and in series with an operating magnet, and wherein the operating magnet is subsequently operated by other contacts of the line relay on deenergizations of the latter by shunting the release relay, a resistance element in series with the operating magnet in circuit between the magnet and release relay, and contacts on the release relay for shunting said resistance element.

9. In a telephone system, an automatic switch having talking conductors incoming thereto, means for operating said switch from its normal position over said incoming talking conductors, means for releasing said switch to its normal position controlled over said incoming talking conductors, and means

responsive to a failure of said connector to release responsive to said releasing control over the incoming talking conductors for opening one of the incoming talking conductors and for maintaining it open as long as the numerical switch is lodged in an off-normal position.

10. In a telephone system, an automatic switch, means for operating said switch from its normal position to effect a connection, a release magnet for restoring said switch to its normal position, a circuit for operating said release magnet to effect the restoration of the switch to its normal position, said circuit being from the grounded pole of the exchange battery through the release magnet to the ungrounded pole of the exchange battery, and a signal relay included in said circuit between the release magnet and the grounded pole of the exchange battery.

11. In a telephone system, an automatic switch, means for operating said switch from its normal position to effect a connection, a release magnet for restoring said switch to its normal position, a circuit for operating said release magnet to effect the restoration of the switch to its normal position, said circuit being from the grounded pole of the exchange battery through the release magnet to the ungrounded pole of the exchange battery, a signal relay included in said circuit between the release magnet and the grounded pole of the exchange battery, said signal relay being common to the release magnets of a plurality of switches.

12. In a telephone system, an automatic switch, means for operating said switch from its normal position to effect a connection, a release magnet for restoring said switch to its normal position, a circuit for operating said release magnet to effect the restoration of the switch to its normal position, said circuit being from the grounded pole of the exchange battery through the release magnet to the ungrounded pole of the exchange battery, a signal relay included in said circuit between the release magnet and the grounded pole of the exchange battery, a high-resistance start relay located in the power apparatus of the exchange, means effective during the operation of the switch for disconnecting said signal relay from the remaining portion of the release magnet circuit and for extending a connection through it to battery by way of the said start relay whereby the start relay is operated, said signal relay being designed and adjusted so that it operates in series with the release magnet but not in series with said high-resistance start relay.

13. In a telephone system, a plurality of lines accessible to a plurality of hunting-type automatic switches, one of said lines being taken for use by said switches when idle whether the other lines are idle or not, means responsive to the last named line being taken

- for use for placing an artificial busy condition thereon and for maintaining it busy to said automatic switches after its seizure has been terminated, and means responsive to a 5 succeeding one of said lines being taken for use by one of said switches for terminating the artificial busy condition of the first line.
14. In a telephone system, a line accessible to a plurality of automatic switches, and 10 means responsive to the seizure of said line by any one of said automatic switches for rendering the said line busy to the remaining automatic switches and for maintaining it busy to all of said automatic switches indefinitely after the seizure of the line has 15 been terminated.
15. In a telephone system, two trunk lines each extending to a switch, a plurality of 20 automatic switches, one of said trunk lines being first choice to all said automatic switches, a group of relays associated with the first choice trunk line, said relay group being responsive to a seizure of said trunk line and to the subsequent freeing thereof for 25 disconnecting the release-trunk conductor of the trunk line from the switch to which it extends and for connecting it instead to a source of guarding potential, said relay group being further responsive to the seizure of the other 30 of said trunk lines to shift the release trunk conductor away from the guarding potential and into connection with the switch to which the trunk line extends.
16. In an automatic switch for supplying 35 ringing current over each of two talking conductors to the corresponding conductors of a telephone line, a source of ringing current superimposed on one pole of the exchange battery, a transformer having a secondary 40 winding connected between one of said talking conductors and the other pole of the exchange battery, and means for operating said switch to connect the other of said talking conductors and the primary winding of said 45 transformer with said source of ringing current.
17. In a ring-back circuit for sending current back to a calling line to signal the calling and called substations thereon, two ringing 50 current-selecting switches, means under the control of the calling subscriber on the calling line for successively setting said switches in accordance with the respective designations of the two substations involved.
18. In a ring-back circuit for use in a telephone system to transmit ringing current back to a calling line to signal the calling and called stations thereon, two switches each 55 having a wiper and a bank of contacts, ringing leads multiplied into certain contacts in the bank of each of said wipers, connections between the wiper of one switch and the remaining contacts in the bank of the other wiper, and connections between the other 60 wiper and the calling line.
19. In a telephone system wherein ringing current is sent back from a ring-back circuit to a calling line over either one or both talking conductors to signal the calling and called stations on the calling line, two switches, each 65 switch having a pair of wipers and a pair of corresponding contact banks, each bank being divided into two sections, and connections between the talking conductors and said wipers and banks such that ringing current is 70 transmitted back in accordance with the setting of one switch only in case both switches are set on the same bank section, and is sent back in accordance with the setting of both switches in case the two are set on different bank sections.
20. In a timing device, a pendulum, a relay, a contact arranged to be closed intermittently by said pendulum only when the latter is swinging with more than a predetermined amplitude, means for setting said pendulum in motion to intermittently close said contact, and a circuit for said relay including said contacts, whereby the relay is caused to operate when said pendulum no 75 longer closes said contacts.
21. In combination, means for giving an alarm responsive to an abnormal condition, said means including a pendulum and means for starting it into motion when an abnormal 80 condition exists and for permitting it to swing freely, and means including a contact intermittently closed by said pendulum only as long as it is swinging for giving an alarm in case the abnormal condition persists until the 85 motion of the pendulum stops.
22. In combination, a pendulum, momentarily applied means for starting the pendulum and for allowing it to attenuate, and means responsive to the attenuation of said 90 pendulum for restarting it.
23. In a telephone exchange system, two sets of power equipment, one set being in operation and the other set being idle, means including a timing device for making successive tests at predetermined intervals, and means responsive to a failure of the operating power equipment to perform predetermined operations for placing the alternate set of power equipment into operation.
24. In a telephone exchange system, two sets of power equipment, one set being in operation and the other set being idle, means including a timing device for making successive tests at predetermined intervals, and means responsive to a failure of the operating power equipment to perform predetermined operations for placing the alternate set of power equipment into operation, and means effective in case the alternate power equipment does not perform the said predetermined operations between successive tests for automatically sounding an alarm indicative of the fact.
25. In a telephone system, power equip- 130

ment, means including a timing device for testing the power equipment and for repeating the test at predetermined intervals, and means responsive to the failure of the power apparatus to perform predetermined operations between successive tests for sounding an alarm indicative of the fact.

26. In a telephone system, power equipment, means including a timing device for testing the power equipment and for repeating the test at predetermined intervals, means responsive to the failure of the power apparatus to perform predetermined operations between successive tests operations for sounding an alarm indicative of the fact, and means for removing the alarm indication in case the predetermined operations are performed between successive testing operations.

27. In a telephone system, a device for generating ringing current, a device for coding the ringing current so that it is delivered to telephone lines in predetermined codes, said coding device being arranged to operate in cycles, two relays arranged to be operated by said coding device at separate points in its operating cycle, a testing device and means for operating it at recurring intervals to test the relays, and means responsive in case either of said relays has failed to operate when tested for sounding an alarm indicative of the fact.

28. In a telephone system, a ringing-current generator, an interrupter for interrupting the ringing current so that it is supplied in interrupted form to called lines, said interrupter being arranged to operate at predetermined intervals, a relay arranged to be operated each time the interrupter operates, means including a timing device for intermittently testing said relay at intervals sufficiently long to enable the interrupter to operate at least once between successive testing operations, and means responsive to the failure of said relay to operate between successive testing operations for sounding an alarm indicative of the fact.

29. In a telephone system, a ringing-current generator, an interrupter for interrupting the ringing current so that it is supplied in interrupted form to called lines, said interrupter being arranged to operate at predetermined intervals, a relay arranged to be operated each time the interrupter operates, means including a timing device for intermittently testing said relay at intervals sufficiently long to enable the interrupter to operate at least once between successive testing operations, means responsive to the failure of said relay to operate between successive testing operations for sounding an alarm indicative of the fact, and a second relay arranged to be maintained operated by the uninterrupted ringing current and to prevent the operation of the first relay in case of a failure of the ringing current.

30. In combination, a plurality of pairs of counting relays, an impulse sending device, means responsive to as many impulses transmitted by said impulse sending device as there are pairs of relays for operating all of said relays and for locking them energized in pairs, a separate pair of relays becoming operated and locked responsive to each transmitted impulse, and circuit arrangements such that said relays respond to the transmission of further impulses from said impulse sending device by deenergizing, one of said pairs of relays being deenergized for each further impulse transmitted.

31. In a ring-back circuit for sending ringing current back to a calling line to signal the calling and called stations thereon, two ringing current selecting switches, means for operating said switches separately, each in accordance with the designation of a separate party on the calling line, means for connecting the calling line with one of said switches, and means for intermittently shifting the calling line from in connection with the said one switch into connection with the other switch whereby the two parties on the calling line are signalled alternately.

32. In a ring-back circuit for use in a harmonic-ringing party-line system to signal calling and called stations on a calling line alternately, a first switch in said ring-back circuit and means for setting it in accordance with the designation of the calling party, a second switch in the ring-back circuit and means for setting it in accordance with the designation of the called party, means for supplying ringing current of the several harmonic frequencies directly and continuously to the contact banks of said switches, means for connecting the calling line to the wipers of one of said switches, and means for intermittently shifting the connection from the wipers of the first switch to the wipers of the second switch, whereby the two parties on the calling line are alternately signalled and each is signalled intermittently.

33. In a reverting call circuit for use in a harmonic ringing party line system to signal calling and called stations on a calling line alternately, a first switch in said ring-back circuit and means for setting it in accordance with the designation of the calling party, a second switch in the ring-back circuit and means for setting it in accordance with the designation of the called party, means for supplying ringing current of the several harmonic frequencies directly and continuously to the contact banks of said switches, means for connecting the calling line to the wipers of one of said switches, and means including a shifting relay for intermittently shifting the connection from the wipers of the first switch to the wipers of the second switch, whereby the two

parties on the calling line are alternately signalled and each is signalled intermittently, said shifting relay being operated over the same path regardless of the particular pair of stations being signalled.

34. In a telephone system, a two motion switch having wipers and arranged to respond in one direction to one digit and to automatically operate in the other direction or to wait for and respond to a second digit by moving in the other direction, and means including a wiper of said switch and contacts with which it comes into engagement during the first movement for determining whether the switch will automatically operate in the other direction or wait for a second digit.

35. In a telephone system, a calling line, a plurality of numerical switches, an non-numerical switching apparatus for automatically connecting said calling line to one of said numerical switches, a relay apparatus in said numerical switch for holding said non-numerical switching apparatus operated, a second numerical switch, means responsive to said relay apparatus in said first numerical switch not completing a holding circuit for said non-numerical switching apparatus for automatically opening the connection to said first numerical switch and for automatically extending said calling line to said second numerical switch, and means in each numerical switch operative if it fails to release for preventing the establishment of a holding circuit for said non-numerical switching apparatus.

36. In a telephone system, means including a non-numerical switch and a numerical switch for extending a connection from a calling line, means in the numerical switch for closing a holding circuit for the non-numerical switch, means for releasing the numerical switch and for opening the holding circuit at the end of the call, and automatic means effective on a second call for preventing the completion of the holding circuit in case the numerical switch is in an off-normal position.

37. In a telephone system, a trunk line extending to an automatic switch, a line relay for operating said switch connected to said trunk line, means for releasing said switch, and means including off-normal contacts for disconnecting said line relay from said trunk line while said switch is being released.

38. In a telephone system, a trunk line extending to an automatic switch, a line relay in said switch bridged across said trunk line, off-normal contacts in said switch for opening said bridge, and a relay controlled by said line relay for shunting said off-normal contacts.

39. In a telephone system, a trunk terminating in an automatic exchange and acces-

sible to switches in the exchange, means for marking the trunk busy when seized by one of said switches, and means for automatically transmitting an alarm signal over the trunk when the same is idle without marking the trunk busy to said switches.

40. In a telephone system, two exchanges, a trunk connecting the exchanges, means for seizing the trunk to complete a talking connection between the exchanges, and means responsive to an unstandard condition in one exchange for transmitting an alarm signal over the trunk to the other exchange without rendering the trunk unavailable for talking connections.

In witness whereof, I hereunto subscribe my name this 4th day of May, A. D. 1929.

NORMAN H. SAUNDERS.
